UNITED STATES PATENT OFFICE.

CHARLES KRUSE, OF SAN LUIS OBISPO, CALIFORNIA.

MECHANICAL MOVEMENT.

1,369,445.

Specification of Letters Patent. Patented Feb. 22, 1921.

Application filed March 22, 1920. Serial No. 367,769.

To all whom it may concern:

Be it known that I, CHARLES KRUSE, a citizen of the United States, residing at San Luis Obispo, in the county of San Luis Obispo and State of California, have invented certain new and useful Improvements in Mechanical Movements, of which the following is a specification.

This invention relates to mechanical movements, and the primary object of the invention is to provide an improved means for changing reciprocatory movement into rotary movement or vice versa.

Another object of the invention is to provide an improved means for changing reciprocatory movement into rotary movement or vice versa, in which all danger of dead center as experienced in the crank shaft is avoided, and in which power will be transmitted continuously to the work during all phases of the movement.

A further object of the invention is to provide a mechanical movement which when used in connection with internal combustion engines or the like will eliminate all trouble now experienced with crank and wrist pin connections and eliminate the uneven wearing of the piston and cylinder.

A further object of the invention is to provide an improved means for connecting the bearing bolts for engaging the sliding plate with the disks carried by the drive shaft, so that the pins can be readily removed without displacing the disks when it is desired to replace the bearings by the bolts.

A still further object of the invention is to provide an improved mechanical movement as above specified, which is durable and efficient in use, one that is simple and easy to manufacture, and one which can be placed upon the market at a reasonable cost.

With this and other objects in view, the invention consists in the novel construction, arrangement and formation of parts, as will be hereinafter more particularly described, claimed and illustrated in the accompanying drawings, in which drawings:

Figure 1 is a vertical sectional view through an internal combustion engine showing the improved mechanical movement applied thereto, the piston being shown in a raised position.

Fig. 2 is an enlarged fragmentary vertical section through the lower portion of the engine, the piston being in its lowered position, and

Fig. 3 is an enlarged vertical transverse section illustrating the means of connecting the slide plate with the shaft carried disks. 60

Referring to the drawings, in detail, wherein similar reference characters designate like and corresponding parts throughout the several views, the letter A indicates the mechanical movement, which is shown 65 in connection with an internal combustion engine B, but it is to be understood that the same can be effectively used with other devices.

The internal combustion engine B is of 70 the ordinary or any preferred type and includes the cylinder 5 having reciprocably mounted therein the piston 6 rigidly carrying the piston rod 7. The cylinder 5 is connected to the shaft casing 8 in the ordinary 75 manner. The shaft casing 8 is relatively narrow in cross section, and includes the straight vertical side walls 9 which form guides for the slide plate 10 of the mechanical movement A which will be hereinafter more fully described. The casing 8 rotatably supports the drive shaft 11 which has keyed or otherwise secured thereto the usual balance or fly wheel 12. The side walls 9 have formed thereon the spaced ribs 85 13, which engage the opposite sides of the slide plate 10 and prevents relative lateral movement of the same in relation to the side walls.

The mechanical movement A as stated includes the slide plate 10 which is of substantially rectangular configuration and is provided with the vertical side faces 14, which slidably engage the inner faces of the side walls 8. The slide plate 10 is provided with 90 the diagonally extending slots 14 and 15, which bisect each other at the central portion of the plate. The plate 10 is further provided with a slot 16 which is positioned at the central longitudinal axis of the plate, 100 and this slot bisects the slots 14 and 15. The upper end of the plate 10 has bolted or otherwise secured thereto as at 17, the lower end of the piston rod 7 and the plate is adapted to be reciprocated in the casing 8 105

by the explosion of the engine and the slot 16 receives the shaft 11 during the reciprocation of the plate. The drive shaft 11 has keyed or otherwise secured thereto the spaced disks 18, between which slidably fits 110 the plate 10 and these disks have eccentrically secured thereto the transversely extending cross bolts 19 and 20, which slide respectively in the slots 14 and 15. The

- bolts 19 and 20 are located at substantially right angles to each other in reference to the axes of the disks 18 and these bolts carry the central bearing sleeve 21, and the end sleeves 22. The central bearing sleeve 21 is provided, so as to permit the free movement of the bolts in the slots, and the end bearings 22 are positioned in suitable openings formed in the disks 18, and prevent displacement of the central bearing sleeve. The bolts 19 and 20 are secured in place by suitable nuts 23, which engage washers 24 which engage against the outer face of one of the end bearings 22 and one, face of one of the disks 18. The washers 24 prevent displacement of the bearing sleeves.
- In operation of the improved device, the bolt 19 slides in the slot 14 while the bolt 20 slides in the slot 15, and the inclined faces of these slots bear against the bearing sleeves of the bolts, and slide the bolts in the slots, and thus turn the disks 18, which in turn transmit their motion to the drive shaft 11. As clearly shown in Fig. 1 of the drawings, when the piston is on its down stroke, the inclined upper face, of the lower half of the slot 15 will engage the bolt 20 and tend to push the same out of the slot. This is owing to the inclination of the upper wall of the slot. Simultaneous with the movement of the bolt 20 toward the outer end of the lower half of the slot, the bolt 19 moves into the upper half of the slot 15 and the upper inclined wall of the same engages the bolt and slides the same toward the inner end thereof. This rotates the disk and guides the bolt 20 into the upper half of the slot 15, at which time the piston will be on its upper stroke, and the lower inclined base of the upper half of the slot 15 will engage the bolt 20 and slide the same inwardly, and turn the disk and move the bolt 19 into the lower half of the slot 14, and the lower inclined base thereof will move the bolt toward the inner end of the slot. This will turn the disk and again move the bolt 20 into the lower half of the slot 15 and the upper inclined face thereof will move the bolt 20 toward the inner end of the slot and turn the disk a portion of a revolution and move the bolt 19 again into the upper half of the slot 14 where the upper inclined surface will act on the bolt 19 and move the bolt 20 into the upper half of the slot 15 as clearly shown in Fig. 2 of the drawings. This completes one revolution of the shaft, and on the next explosion of the engine, the shaft will be turned in the same manner.
- From the foregoing description, it can be seen that an improved means is provided for transmitting reciprocatory movement into rotary movement or vice versa, which can be effectively used for internal combustion engines and the like.

Changes in details may be made without departing from the spirit or scope of the invention; but,

I claim:

1. A mechanical movement comprising a slide arranged for reciprocatory movement, a rod connected to the slide, the slide having diagonally extending bisecting slots formed therein, and a slot arranged intermediate the diagonal slots, a shaft arranged for rotary movement, a pair of spaced disks keyed to the shaft arranged to slidably receive the slide block therebetween, the last-mentioned slot being arranged to receive the shaft, and transversely extending members eccentrically carried by the disks and arranged to slidably engage in said diagonally extending slots. 75
2. A mechanical movement comprising a shaft arranged for rotary movement, a pair of spaced disks keyed to the shaft, a slide arranged for reciprocatory movement slidably mounted between said disks and having a longitudinally extending slot therein arranged to receive the shaft, the slide having diagonally extending bisecting slots bisecting the longitudinally extending slots, transverse bolts eccentrically carried by the disks arranged to slidably engage in said diagonally extending slots, the bolts having a bearing sleeve arranged intermediate their ends for engaging the walls of the slot, and end bearing sleeves carried by the disks. 80
3. In an internal combustion engine, a cylinder, a crank case having straight side walls, a piston reciprocably mounted in the cylinder, a slide mounted in the crank case and engaging said straight side walls, a piston rod connecting the slide and piston, a shaft rotatably carried by the case, disks keyed to the shaft, the slide having a longitudinally extending slot formed therein arranged to receive the shaft, and diagonally extending bisecting slots bisecting the longitudinally extending slot, and eccentric pins carried by the disks arranged to slidably engage in said diagonally extending slots. 95
4. In an internal combustion engine, a cylinder, a case connected to the cylinder, the case having straight side walls, guides secured to the straight side walls, a piston reciprocably mounted in the cylinder, a slide mounted in said guides, a piston rod connecting said piston and slide, a shaft rotatably carried by the case, a pair of spaced disks keyed to the shaft and arranged to slidably receive the slide therebetween, the slide having a longitudinally extending slot arranged to receive the shaft and diagonally extending cross slots bisecting the longitudinally extending slot, and eccentric pins carried by the disks and arranged to slidably fit in said diagonally extending slots. 100
